UNITED STATES PATENT OFFICE.

CHARLES HVASS, OF NEW YORK, N. Y., ASSIGNOR OF ONE-HALF TO
LAZARUS KAHNER, OF SAME PLACE.

DESIGN FOR A HEAD-FORMER FOR CIGARS.

SPECIFICATION forming part of Design No. 22,595, dated July 4, 1893.

Application filed May 15, 1893. Serial No. 474,351. Term of patent 14 years.

To all whom it may concern:

Be it known that I, CHARLES HVASS, a citizen of the United States, residing at New York, in the county of New York and State of New York, have invented and produced a new and original Design for Head-Formers for Cigars, of which the following is a specification.

The essential feature of my design consists in the shape, or configuration, of the surfaces lying adjacent to the head rest and coinciding therewith and in the shape of other parts extending from the head rest.

In the drawings Figure 1 is a plan view; Fig. 2 a front elevation; Fig. 3 a rear elevation; Fig. 4 a bottom plan view; Fig. 5 an end elevation looking in the direction of the arrow *a*, Fig. 1, and Fig. 6 an end elevation looking in the direction of the arrow *b*, Fig. 1.

The head former comprises a block of irregular outline in plan, and substantially rectangular in front, rear and end elevations. The block 1 has an extension 2, the ends of which are rounded, and a substantially rectangular extension 3. Traversing the block 1 and lying between it and the extension 3 is a conoidal aperture or head rest 4, above which lies an

inverted **V** shaped slot 5. The surface 6 of the block is substantially flat, and is partially broken by the slot 5, which forms an irregular ledge 7. Opposite the ledge 7 is a ledge 8 irregular in outline, and which defines the opposing side of the slot 5. The ledge is one side of a hump 9, which rises upwardly from the aperture 4, and above the surface 6 of the block 1, and which slopes downwardly to the rear of the extension 3, as seen in Fig. 6. The top of the hump 9 is rounded and it descends laterally to a depression 10 in the extension 3, forming a wall 11 on one end and another wall 12 on the rear. Within the depression 10 are circular apertures 13, and immediately below the aperture 4 is a downwardly extending cylindrical lug 14.

Having described my design, I claim—

The design for a head former for cigars, substantially as herein shown and described.

Signed at the city, county, and State of New York this 11th day of May, 1893.

CHARLES HVASS.
